217,347

COMBINED INPUT/OUTPUT AND VISUAL DISPLAY UNIT FOR A COMPUTER

Mario Bellini, Milan, Italy, assignor to Ing. C. Olivetti &
C., S.p.A., Turin, Italy, a corporation of Italy

Filed Oct. 4, 1968, Ser. No. 13,843

Term of patent 14 years

Int. Cl. D14—02

U.S. Cl. D26—5

FIG. 1

FIG. 2

FIG.3

FIG.4

FIG. 1 is a perspective view of a combined input/output and visual display unit for a computer showing my new design;

FIG. 2 is a side elevation view as viewed from the right in FIG. 1;

FIG. 3 is a side elevation view as viewed from the left in FIG. 1; and

FIG. 4 is a rear elevation view thereof.

I claim:

The ornamental design for a combined input/output and visual display unit for a computer, as shown.
